BABY WALKER

Viktor Schreckengost, Cleveland Heights, Ohio,
 assignor to The Murray-Ohio Manufacturing
 Company, Cleveland, Ohio, a corporation of
 Ohio

Application December 28, 1949, Serial No. 6,870

Term of patent 14 years

(Cl. D14—14)

To all whom it may concern:

Be it known that I, Viktor Schreckengost, a citizen of the United States, residing at Cleveland Heights, county of Cuyahoga, and State of Ohio, having invented a new, original, and ornamental Design for Baby Walker, of which the following is a specification, reference being had to the accompanying drawing, forming a part thereof.

In said annexed drawing:

Fig. 1 shows the baby walker of my design in perspective as viewed from a point at the side and slightly to the front;

Fig. 2 is a top plan view of the walker; and

Fig. 3 is a rear elevational view of the walker.

I claim:

The ornamental design for a baby walker, substantially as shown.

VIKTOR SCHRECKENGOST.
